(57) **CLAIM**

The ornamental design for an information handling system touch detection surface control icon user interface as shown and described.

DESCRIPTION

FIG. 1 is a top plan view of an information handling system touch detection surface control icon user interface comprising the present invention;

FIG. 2 is a front left upper perspective view thereof shown on an information handling system touchpad with the information handling system in a clamshell orientation;

FIG. 3 is a top plan view thereof shown on the information handling system touchpad with the information handling system in a planar orientation; and,

FIG. 4 is a left upper perspective view thereof shown on an information handling system touchpad with the information handling system in a planar orientation.

The broken lines in the drawings depict an environmental information handling system only and form no part of the claimed design.
